STOKER

William Thompson Hanna, Cincinnati, Ohio

Application December 13, 1930, Serial No. 502,039

2 Claims. (Cl. 110—101)

This invention relates to stokers in general and particularly such as may be used upon locomotives and the like.

One of the objects of the invention is to provide a stoker which is simple and durable in construction and efficient in action.

This and other objects, general and particular, will be best seen by reference to the accompanying drawings, in which:

10 Fig. 1 is a vertical axial section through a stoking mechanism as shown mounted on the back head of a locomotive;

Fig. 2 is a top plan view (partly in section) showing fuel manipulating worms;

15 Fig. 3 is an enlarged side elevation (partly in section) of a tapered worm embodying the invention;

Fig. 4 is a detailed side elevation of the worm shown in Fig. 3, illustrating diagrammatically the 20 double taper profile of the periphery of the spiral vane; and,

Fig. 5 is a partial longitudinal sectional view of the worm shown in Fig. 3, showing characteristics of the vane structure in relation to the 25 hub portion.

Referring particularly to Fig. 1 of the drawings, the stoker mechanism is shown in connection with the fire box 14 of a locomotive in which the usual back head 15 is provided with a firing opening 16. Surrounding the firing opening and rigidly mounted on the back head is a fuel supply housing 17 having the usual hand-firing opening 18. Mounted upon the fuel supply housing 17 and positioned within the firing opening 16 are suitable fuel distributing means including a multiple blast chamber 19 and a distributor plate 20. Steam pressures of different intensities may be supplied to different portions of the blast chamber 19.

40 The lower portion of the housing 17 forms a flanged conduit section to which is rigidly attached an extension conduit 21, having its outer end arranged to form a universal bearing support for the forward end of a transfer conduit 45 22. This bearing support is accomplished by means of a partial spherical recess arranged in the end of the conduit 21, in which is journaled a member 23 in the form of a section of a sphere rigidly secured to the transfer conduit 22 and 50 retained in position by a retaining ring 24 rigidly secured in any suitable manner to the end face of the conduit. The extension conduit 21 is preferably substantially circular in cross-section with an expanding cross-sectional area as it 55 approaches the firing opening. The conduit 22

receives fuel from a hopper conveyor (not shown) customarily located beneath the locomotive tender.

Rotatably mounted in the conduit 22 and suitably driven by mechanism (not shown), is a transfer conveyor 25 in the form of a spiral vane or worm and its forward end projects a substantial distance into the conduit 21. The blade of the conveyor 25 has its forward end tapered for a distance substantially the extent of its projection beyond the end of the conduit 22, and it has been found in practice that this assists in elevating the fuel into the fuel supply housing 17.

Referring particularly to Figs. 1 and 2, it will be seen that within the housing 17 and adjacent the firing opening 16 there are mounted revolvable members 53 and 54. These members form fuel conditioning and handling means which act upon the fuel entering the housing from the 20 conduit 22 to place the same in the most advantageous condition for presentation to the fire and particularly to reduce any substantially solidified masses thereof which may be formed as a result of coherence of the parts or particles 25 under pressure or otherwise. Such means also serves to advance the conditioned fuel to the distributing means in a manner to insure effective action thereof. The members 53 and 54, as shown, are in the form of spiral worms or 30 vanes tapering toward their free forward ends. This taper may be made to vary in degree in different portions of the member as diagrammatically illustrated in Fig. 4. It will be seen that the taper in the forward portion is greater 35 than in the rear portion, the change in taper occurring at a point substantially midway in the length of the vane or blade. With this construction the fuel handling capacity of each 40 worm, or screw, is materially increased at its larger end. A sectional view of one of these members is shown in Fig. 5 in which it will be evident that the rear face of the vane or blade is substantially at a right angle to the axis of rotation and the forward face is arranged at a 45 substantial angle to the rear face. This formation of the member has been found to give very satisfactory results.

Referring again particularly to Fig. 2, the fuel supply housing 17 has a portion 55 arranged in 50 the form of a ledge over which the fuel flows as it is carried into the firing opening by the action of the members 53 and 54. Not only is it desirable to provide a control for the volume of fuel passing over the ledge 55, but it is also 55

advisable to have means for directing more or less volume toward the right side or toward the left side of the firing opening as occasion requires. This result may be accomplished in various ways, but I have here shown laterally adjustable members 56 and 57 slidably mounted in the respective sides of housing 17 and slidable over the ledge 55 and blast chamber 19. The members 56 and 57 are pivotally connected to operating levers 58 and 59 by means of which the lateral position of the said members may be controlled each independently. In this way, greater or lesser volume may be permitted to flow over the said ledge and the quantities of fuel directed toward the right or left sides may be varied. These adjustable members are preferably arranged for adjustment in an angular direction relative to the edge of the ledge 55 as shown clearly in Fig. 2.

20 Power for the operation of the stoker may be supplied by any suitable power device and transmitted therefrom to the moving elements in any convenient manner.

Referring to Figs. 1 and 3, the worms or fuel-handling members are driven from a worm 80 suitably driven by an engine (not shown). The worm 80, through suitable worm gears 84, drives shafts 85 and 86, which respectively drive the worms 53 and 54. Referring to Fig. 3, the shaft 30 86 drives its worm 54 through bevelled miter gears 89 and 90. Similar miter gears are provided for the worm 53.

In the operation of the stoker mechanism, the conveyor 25 transfers fuel forwardly from 35 the locomotive tender (not shown) and delivers the coal into the fuel-supply housing 17, where, due to the contour of this housing, the fuel is presented to the fuel-handling or conditioning members 53 and 54. Further movement of the 40 fuel is controlled by the action of these members 53 and 54 and the fuel is thereby caused to pass into the fire box, above the level of the fire, flowing over the ledge 55 which extends across the firing opening. The fuel subsequently falls upon 45 and flows by gravity over the blast chamber 19 and upon the distributing plate 20 from which it is scattered over the fire by means of the blasts of steam emitting from the jets of the blast chamber.

The form and arrangement of the fuel-handling and conditioning members 53 and 54 insure efficient operation thereof and the passage of the fuel to the distributing means in the most advantageous manner and condition. The driving 5 mechanism for the fuel-handling and conditioning members in the form shown is an assembled unit.

As many other embodiments may be made of the features of this invention without departing 10 from the scope thereof, it is to be understood that all matter herein set forth or shown, is to be interpreted as illustrative and not in a limiting sense.

I claim:

1. In a stoker mechanism, the combination with a fire box having a fuel entrance, of a conduit provided with means for moving fuel from a source of fuel supply to said entrance, the lower forward edge of said conduit providing a ledge 20 over which fuel flows into said entrance, means for distributing fuel fed to said entrance upon and over the fire, and fuel conditioning and regulating means comprising a rotary worm 25 interposed between said fuel moving means and said distributing means and recessed in said conduit generally below and to the rear of said edge and extending transversely of said conduit, for transforming the fuel into form relatively thinner than the bulk of the fuel in the conduit, said 30 worm being tapered and the taper of the larger part of said worm having a smaller angle of inclination than the taper of the smaller part.

2. For use in a locomotive stoker having a conduit extending to and embracing a firing 35 opening of a fire box, the lower forward edge of said conduit forming a ledge over which fuel flows; a tapered fuel handling screw recessed in said conduit generally below and to the rear of said ledge and pointing from the side of said 40 conduit toward the center thereof, said screw having a single flight and the angle of inclination of the taper of said screw being greater at the small end of the screw than at the larger end thereof whereby the fuel handling capacity 45 at the larger end is materially increased.

WILLIAM THOMPSON HANNA.
